[57] CLAIM

The ornamental design for a shoe outsole as shown and described.

DESCRIPTION

FIG. 1 is a bottom plan view of a shoe outsole showing my new design;

FIG. 2 is a sectional view taken along line 2—2 of FIG. 1;

FIG. 3 is a sectional view taken along line 3—3 of FIG. 1; and

FIG. 4 is a sectional view taken along line 4—4 of FIG. 1.

The top of the outsole, not shown, is substantially plain and conventional.

FIG. 1.

FIG. 3.

FIG. 2.

FIG. 4.
